UNITED STATES PATENT OFFICE

GEORGE H. ARMITAGE, OF PROVIDENCE, RHODE ISLAND, ASSIGNOR TO UNITED LACE & BRAID MANUFACTURING CO., OF PROVIDENCE, RHODE ISLAND, A CORPORATION OF RHODE ISLAND

PROCESS OF AND APPARATUS FOR TIPPING LACES

Application filed August 23, 1927. Serial No. 214,935.

- This invention pertains to a process of and apparatus for tipping laces, for example shoe laces, and is intended to facilitate, expedite and cheapen the manufacture of such laces.
- 5 While in the embodiment of means herein illustrated the invention is more particularly described with reference to the formation of non-metallic tips of that type in which organic material having suitable characteristics is associated with the normally limp and pliable lace material so as to stiffen the latter locally, thereby providing a tip, and while in 10 its specific application the invention relates to the formation of a tip by insertion into and subsequent compression of a slug of celluloid or similar material within the end of a tubular textile lace, the invention is not thus limited, since in its broader aspects it may be 15 found useful in connection with the application of metallic or other tips exterior to the lace material or embedded in or enclosed thereby, and to the formation of tips upon lace material other than tubular and whether 20 of textile or other material.
- 25 For illustrative purposes the invention is hereafter described with reference to the formation of tips of that type in which a slug of celluloid is first inserted in a tubular textile braid and then subjected to heat and pressure, 30 in the presence of a solvent for celluloid if desired, to cause the celluloid and textile fibers firmly to adhere and to give the tip the desired shape and finish.
- Such tips have heretofore been made by a 35 slow and laborious hand operation. In the practice of this manual operation the worker provides himself with a supply of short pieces or slugs of celluloid, flat or round, of a length substantially equal to that of the desired tip, 40 and after inserting one of these slugs in the end of the tubular lace usually moistens the enclosing fabric with a celluloid solvent, and then subjects the tip to pressure in a press having dies shaped to give the tip the desired 45 form. While this manual process results in the production of an acceptable tip, it is costly and for this reason impractical, except as applied to the more expensive grades of lace.
- I am also aware that certain suggestions 50 have been made to the effect that the tip-
- forming slugs might be fed into the lace material during the manufacture of the latter on the braiding machine, but I regard these suggestions as highly impractical for several reasons, among which may be mentioned the 55 difficulty, if not impossibility, of producing laces of uniform length in this manner, and, so far as I am aware, no practical process or automatic machine has heretofore been devised which can produce satisfactory tips of 60 this character with rapidity, efficiency and certainty.
- In the accompanying drawings I have illustrated by way of example mechanism capable of performing my improved process expeditiously and reliably, and in the drawings: 65
- Fig. 1 is a rear elevation of the machine, the lower part of the base being broken away;
- Fig. 2 is a fragmentary front elevation omitting certain parts and having the central 70 portion of the casing broken away, disclosing the main cam shaft and drive clutch in section;
- Fig. 3 is a fragmentary plan view showing the central portion only of the machine. 75
- Fig. 3^a is a fragmentary and more or less diagrammatic plan view illustrating the means for actuating the gripper devices and the anchor shafts;
- Fig. 4 is a fragmentary vertical section to 80 larger scale, substantially on the line 4-4 of Fig. 3;
- Fig. 5 is a fragmentary vertical section substantially on the line 5-5 of Fig. 3;
- Fig. 5^a is a section on the line 5^a-5^a of 85 Fig. 5 illustrating details of one element of the drive clutch;

55 Fig. 25 is a horizontal section on the line 25—25 of Fig. 23;

Fig. 26 is a vertical section to larger scale on the line 26—26 of Fig. 21;

60 Fig. 27 is a vertical section, partly in elevation and to larger scale, on the line 27—27 of Fig. 21, or the line 27—27 of Fig. 28;

Fig. 28 is a vertical section on the line 28—28 of Fig. 27;

65 Fig. 28^a is a diagram illustrating the relations of the levers and cams shown in Fig. 28;

Fig. 29 is a fragmentary horizontal section on the line 29—29 of Fig. 27;

Fig. 30 is a plan view, partly in section, of the base portion of the tip-inserting unit substantially on the plane of line 30—30 of Fig. 70 22;

Fig. 30^a is an end view of one of the lace end holders removed from the machine;

Fig. 30^b is a section to large scale substantially on the line 30^b—30^b of Fig. 30, but showing the lace end holder in operative position; 75

Fig. 31 is a side elevation of the base of the tip-inserting unit, certain parts being removed;

Fig. 32 is a fragmentary side elevation of 80 one of the tip-inserting needles removed from the machine showing a tip-forming slug within the needle and the slug discharging plunger in retracted position;

Fig. 32^a is a plan view of the needle, to enlarged scale, removed from the machine;

Fig. 33 is a view similar to Fig. 32 but showing the needle with the slug inserted in the end of a lace and with the discharging plunger advanced to operative position; 90

Fig. 34 is a view similar to Fig. 33 but showing the needle retracted from the lace and the plunger still in advanced position, holding the slug within the end of the lace;

Fig. 35 is a vertical section on the line 35—35 of Fig. 30;

Fig. 36 is a diagram illustrating the sequence of operations of the principal actuating cams;

Fig. 37 is a vertical section on line 37—37 of Fig. 38 illustrating details of a modified mechanism comprising a rotary turret for presenting the lace material to the tip-inserting means and the dies; 100

Fig. 38 is an end elevation of the rotary 105 turret shown in Fig. 37;

Fig. 39 is an end elevation of a die supporting plate forming a part of the mechanism shown in Fig. 37;

Figs. 40 to 43 are diagrammatic perspective views illustrating the cycle of operations of the machine; and 110

Fig. 44 is a diagrammatic view illustrating the operation of the arrangement shown in Figs. 37 to 39, inclusive. 115

Frame and driving mechanism

Referring to the drawings and more particularly to Figs. 1, 2, 3, 4, 5, 6, 7, 8, 12 and 13, the machine preferably comprises a standard or column 1 provided with an extended base not shown, adapted to furnish a firm support for the machine parts. Preferably, the standard or column 1 is hollow and is provided at its upper end with a cap 2 constituting a table for holding the upper portion of the machine. Upon this table I mount a casting 3 which houses the major part of the main actuating mechanism and which forms the frame proper of the machine. The front 120 125 130

wall of this casing or housing 3 is furnished with an outwardly projected boss 4 (Figs. 3 and 4) and with a corresponding inwardly directed boss 5 (Figs. 4). A bore extending through the bosses 4 and 5 furnishes a bearing for a main drive shaft 6 (Figs. 2 and 4) upon the outer end of which I mount a pulley 7 (Fig. 3) or other suitable drive element. Preferably I provide this pulley with a hand wheel 8 so that the machine may be turned over by hand if desired.

At its inner end the shaft 6 carries a worm 9 (Figs. 2 and 4) which meshes with a worm wheel 10 normally free to turn upon the main cam shaft 11. The cam shaft 11 is journaled in suitable bearings 12 and 13 (Fig. 2) carried by the casing 3 and has mounted thereon the principal actuating cams hereafter more specifically referred to. An annular flange 14 (Figs. 2 and 5^a) projects from one side of the worm wheel 10 and this flange houses a spider 15 which may turn freely within the flange 14. The spider 15 is furnished with one or more pockets, preferably three, for the reception of clutch rollers 16. A sleeve 21, concentric with shaft 11, extends through a central bore in the spider 15 and the exterior surface of this sleeve 21 is furnished with recesses having inclined or wedge-like faces (Fig. 5^a) adapted to force the rolls 16 into clutching engagement with the inner surface of the flange 14 when the spider occupies a certain position, thereby clutching the worm wheel 10 to the sleeve 21.

The sleeve 21 is keyed to the cam shaft 11 and constitutes an elongate hub for a gear 18 which is fixed to one end of the sleeve. The sleeve 21 is furnished with a radial flange 19 having an annular groove 20 (Fig. 5). The spider 15 is also provided with a radial flange 15^a (Fig. 5^a) having a similar groove 20^a (Fig. 5^a) which is opposed to the groove 20. A pin 22 (Fig. 5) projects from the flange 19 into the annular chamber formed by the opposed grooves and a similar pin 23 (Fig. 5^a) projects into this chamber from the flange 15^a. A compression spring 24 is disposed within the chamber formed by the opposed grooves and has its opposite ends bearing against the pins 22 and 23 respectively. The flange 19 is furnished with a radial ear 25 (Fig. 5) and the flange 15^a is provided with a similar radial ear 26 (Fig. 5^a).

A pivoted stop dog 27 (Fig. 5) is mounted upon a stub shaft 28 secured to a bracket web 29 projecting from the inner surface of the casing 3. This stop dog 27 is wide enough to engage both of the ears 25 and 26 simultaneously and when so engaged the dog prevents rotation of the flange 19 with its gear 18, and also of the spider 15.

The stop dog 27 is normally retained in the operative position shown in Fig. 5 by means of a plunger 30 sliding in a bore in a housing

31 carried by the bracket 29 and which is forced outwardly by means of a spring 32.

The dog 27 is provided with an arm 33 (Figs. 5, 12 and 13) which normally occupies the deepest part of a cam notch 34 in an axially movable shaft 35 (Figs. 5, 12 and 13). The shaft 35 slides in aligned openings in the bracket 29 and in the wall of the casing 3 respectively, and is normally held in the position shown in Fig. 12 by means of a spring 37 bearing at one end against the wall of the casing 3 and at its other against a collar 36 secured to the shaft 35.

A vertical shaft 38 is journaled in a boss 39 (Fig. 5) on the inside of the casing 3 and this shaft projects up through the top of the casing and is furnished at its upper end with a control handle 40. At a suitable point this shaft is furnished with a flattened or slabbed-off portion 41 (Fig. 12) engaged by a spring-pressed ball 42 which tends to hold the shaft in normal position, as shown in Figs. 2 and 12.

The shaft 38 is furnished with a fork 43 engaging a flattened portion 44 of the shaft 35. This fork plays between the collar 36 and another collar 45 fixed to the shaft 35. The shaft 38 is also furnished with a latch-releasing arm 46 (Fig. 12) adapted to engage one end 47 of a lever pivotally supported at 48 and whose other end 49 is connected to a vertically movable detent 50 which is adapted at times to engage a notch 51 in the shaft 35. The weight of the arm 46 is such as to tend to raise the detent 50 into engagement with the notch whenever the notch is brought into registry with the detent.

When the machine is idle, the control handle 40 occupies the position shown in Figs. 2, 3 and 5 and the shaft 35 is so positioned that the arm 33 of the stop dog 27 is in the deep part of the notch 34 in the shaft 35. The stop dog 27 thus engages both of the ears 25 and 26 so that, as above stated, the gear 18 and the spider 15 are positively prevented from rotating in the direction of the arrow shown in Fig. 5. These parts are likewise positively held against reverse rotation by means of a second dog 52 (Fig. 5) pivotally supported at 53 and normally held in engagement with the ears 25 and 26 by means of a spring 54 conveniently mounted upon the dog 27.

To start the machine, the operator swings the handle 40 in a counterclockwise direction, thus moving the shaft 35 to the left (in Fig. 12) until the notch 51 registers with the detent 50. The detent rises into engagement with the notch and thus holds the shaft in its new position in opposition to the spring 37. In moving to the left the inclined cam surface of the notch 34 engages the arm 33 of the stop dog 27 and swings the stop dog in a counterclockwise direction, as shown in Fig. 5, until it disengages both of the ears

25 and 26. Since the gear 18 is at this time stationary, being so held by the resistance of the parts driven thereby, the energy of the spring 24, reacting against the pin 22, causes the pin 23 with the spider 15 to make a partial revolution about the shaft, thus bringing the rollers 16 into operative position and clutching the worm wheel 10 to the sleeve 21, thereby starting the cam shaft 11 and the gear 18 into rotation.

10 When it is desired to stop the machine, the operator swings the control handle 40 in a clockwise direction (Fig. 12) until the releasing finger 46 engages the lever arm 47 and lifts the latter so as to disengage the detent 50 from the notch 51. The spring 37 then returns the shaft 35 to its normal position, permitting the arm 33 of the stop dog 27 to return to the deep part of the notch 34. The 15 stop dog is now swung down by the spring 30 into the path of the ears 25 and 26.

20 During the rotation of the cam shaft the ear 26 of the spider 15 is in advance of the ear 25 so that it is stopped by engagement 25 with the dog 27 before the ear 25 comes into engagement with the latter, thus providing sufficient time for disengagement of the clutch before the ear 25 engages the dog. During this period of relative movement the 30 spring 24 is compressed and as the retaining dog 52 drops behind the ear 25 at substantially the same instant that it is engaged by the stop 27, any reverse movement is prevented and the energy of the spring 24 is 35 available for use in the next starting operation.

30 The above mechanism is in general similar to that disclosed in my prior Patent No. 1,423,948, July 25, 1922, and I do not claim it broadly herein.

Shuttle drive

40 A bevelled pinion 55 is fixed to the shaft 11 near the left hand end of the latter (Fig. 2) and this pinion meshes with a bevelled pinion 56 (Figs. 2 and 4) mounted upon a short shaft journalled in a bearing boss 57 carried by the casing 3. This shaft projects out through the front wall of the casing and 45 carries a sprocket wheel 58. (Fig. 3). A chain 59 (Fig. 8) engages the sprocket wheel 58 and this chain also engages and drives a sprocket wheel 60 (Figs. 7 and 8) carried by a shaft 61 journalled in a bearing boss 62 50 projecting from the lower part of the tubular supporting column 1. The shaft 61 projects into the interior of the column 1 and is furnished at its inner end with a crank disk 63 having a crank pin 64. The pin 64 turns in 55 a block 65 which slides transversely in a cross-head 66 carried by a vertically movable rack bar 67.

60 The upper part of the bar 67 (Fig. 8) is furnished with rack teeth 68 meshing with a 65 pinion 69 on a shaft 70 journalled in a box

70 which is housed within the column 1 and secured thereto by means of bolts engaging an attaching flange 71^a. Shaft 70 is furnished at its forward end, outside of the column, with a gear 72 meshing with a gear 72^a 75 carried by a shaft 73 also journalled in the box 71. The shaft 73 projects out through the opposite wall of the column 1 and is journalled in a sleeve 74 suitably secured to the column. A shuttle driving pulley 75 is fixedly secured to the outer end of the shaft 73. This pulley has a substantially flat face 76, provided with flanges at its opposite edges.

80 Preferably the shaft 73 is provided with a worm or screw-thread 77 which engages with a worm segment 78 carried by a shaft journalled in a bracket 82. This shaft is provided at opposite ends with gear segments 79, of which one is shown in Fig. 8. These segments 79 mesh respectively with racks 80 85 formed upon sleeves adapted to slide upon guide bars 81 mounted upon bracket arms 82^a. Each of the rack sleeves 80 is provided with a traverse guide member 83 the purpose 90 of which will hereafter be described.

95 Casing 3 (Figs. 1, 2 and 3) supports arms 85 and 86 projecting from its opposite sides and attached thereto in any suitable manner as by means of bolts. These arms extend outwardly from the central casing to a substantial distance, which, as a practical matter, should be substantially greater than one-half of the length of the longest lace which is to be made upon the machine.

100 Each of the arms 85 and 86 is provided near its outer end with a pair of guide pulleys 87 and 88. The outer ends of the arms 85 and 86 are also furnished with upwardly projecting brackets or supports 85^a and 86^a to which the opposite ends of a shuttle guiding 105 rail 89 are secured. This rail 89 extends transversely across the entire width of the machine.

110 The rail 89 is preferably flat (Figs. 5 and 6) and has bevelled front and rear edges, and a shuttle or lace distributing carriage 90 is arranged to reciprocate along this rail. Preferably the carriage comprises an upper portion of substantially rectangular contour 115 (Fig. 3) provided with front and rear grooved anti-friction rollers 91 and 92 respectively (Figs. 3, 6 and 11). The rollers 91 of the front pair engage the forward edge of the rail 89 while the rollers 92 of the rear pair engage the rear edge of the rail thus 120 securely retaining the carriage upon the rail while permitting it to travel endwise of the rail with but little friction.

125 The upper or body portion of the shuttle or carriage 90 is furnished with a guide eye 94 for the lace material and from the rear edge of the upper part of the carriage a leg 95 extends downwardly and is furnished at its lower end with a pair of grooved guide rolls 96 and 97 (Fig. 11) between which the 130

lace material passes. Preferably, for a purpose hereafter more fully indicated, the leg 95 is bent at the point 98 (Fig. 6) so that the delivery point of the lace material, defined by the rollers 96 and 97, is disposed at a point substantially directly below the rear edge of the rail 89.

Auxiliary grippers

- 10 Referring to Figs. 3^a, 4, 5, 6, 9 and 10, a shaft 99 extends transversely of the casing 3 at a point substantially below the rail 89. This shaft is suitably journaled in the walls of the casing and is furnished at about its middle point with gear teeth 100 constituting a pinion adapted to mesh with rack teeth upon a bar 101 (Fig. 6) which is adapted to reciprocate from front to rear in a suitable guide opening in a part 102 of the casing 3. 15 The forward end of the bar 101 is connected to the upper end of a lever 103 journaled to swing on a shaft 103^a and provided at an intermediate point with a cam follower roll 104. This roll 104 engages a cam 105 mounted upon the shaft 11 above described. This cam is adapted to swing the lever 103 rearwardly, thus turning the shaft 99 in a counterclockwise direction (Fig. 6). A spring 20 105^a or equivalent means moves the bar 101 in the opposite direction.

Referring particularly to Figs. 3^a and 9, the shaft 99 carries a pair of auxiliary gripper devices 106 and 106^a arranged respectively at opposite sides of the rack bar 101 and within the casing 3. Each of these gripper devices comprises a radial arm (Figs. 14 and 14^a) furnished at its outer end with a transversely extending finger 107 carrying a fixed gripper jaw 108 at its end. A resilient gripper jaw 109 cooperates with the fixed jaw 108. This resilient jaw preferably consists of a strip of spring metal attached to the member 107, the opposed faces of the jaws 108 and 109 diverging to provide a flaring 40 entrance for the lace material. In order to guard against too deep entry of the lace material between the jaws 108 and 109 I provide the jaw 109 with an ear 110 adapted to overlap the end surface of the jaw 108, this forming a positive stop for the lace material. 45 The auxiliary gripper devices 106 and 106^a are disposed upon the shaft 99 with their arms 107 directed toward each other as shown in Fig. 3^a.

Anchor devices

- 55 The opposite ends of the shaft 99 are furnished with cone centers 111 (Fig. 9) which enter conical sockets in the inner ends of shafts 113 and 114 respectively (Fig. 3^a). 60 The shafts 113 and 114 are aligned with each other and with the shaft 99 and at their outer ends are furnished with conical sockets adapted to receive the conical ends of set screws 115 and 116 (Fig. 1) respectively 65 mounted in the brackets 85^a and 86^a. Shafts

113 and 114 will hereafter be referred to as the "anchor" shafts since each of these shafts carries an anchor or measuring hook hereinafter to be described.

Each of the shafts 113 and 114 is provided rear its inner end with a collar 117 and 118 (Figs. 3 and 3^a) respectively and these collars are furnished with driving dogs or pins 117^a and 118^a respectively which enter sockets in adjacent main gripper devices herein-after described.

75 As stated, each of the shafts 113 and 114 is furnished with an anchor device, indicated respectively at 119 and 120. Each of these anchor devices comprises a hub (Fig. 15) 80 which is adjustable lengthwise of its shaft and which may be secured in adjusted position by means of a set screw or other suitable device. Each of these anchors or lace measuring hooks comprises a pair of arms extending radially in opposite directions, from its hub, the arms of the anchor 120 being designated 121 and 122 respectively and the arms of the anchor 119 being designated 121^a and 122^a respectively. Preferably each of the 85 arms of the anchor devices is curved or hooked at its outer end, the ends of the hooked portions projecting in the direction of the rotation of the anchor device.

90 Between each auxiliary gripper and the adjacent end of the shaft 99 I mount a sleeve 123 (Fig. 9) which is free to turn upon the shaft. Upon each of the sleeves 123 I mount a sleeve 124 which is fixedly secured to the sleeve 123 by means of a set screw, key, or otherwise. The sleeves 124 constitute the hubs of gears 125 and 125^a (Figs. 3 and 3^a) respectively, which are located inside of the casing 3. The sleeves 123 project out through the walls of the casing 3 and at their outer 95 ends carry the main gripper devices indicated at 126 and 126^a respectively.

Main grippers

100 These main gripper devices are of like construction and as shown in Fig. 10 each comprises a body portion 127 having oppositely directed radial arms 128 and 129. The outer ends of the respective arms 128 and 129 are shaped to provide fixed gripper jaws 130 and 131 respectively. Each arm is furnished with a radial slot for the reception of a movable gripper jaw, the jaw 132 cooperating with the fixed jaw 130, and the jaw 133 cooperating with the fixed jaw 131. Each of 110 the movable jaws 132 and 133 is fixed to a short shaft journaled in the corresponding arm and each movable jaw is connected by a link 134 to a plunger 135 in a suitable bore in the body 127. A spring seated in each 115 bore tends to force its plunger outwardly and the parts are so arranged that as the jaw swings from open to closed position the point of connection of the link 134 to the jaw passes from one side to the other of the axis 125 120 130

of the plunger 135. Thus the spring holds the jaw either in open or closed position.

As shown in Figs. 10^a and 10^b each of the shafts carrying the movable jaws is furnished 5 with an actuating finger 132^a at a point outside of the corresponding arm of the gripper body and each of the movable jaws is also provided with an actuating arm 136 (Fig. 10). The arm 136 is used for opening the 10 jaw while the finger 132^a is employed in closing the jaw.

The gears 125 and 125^a of the respective gripper devices mesh with corresponding gears 137^a and 137 (Fig. 3^a) upon a transverse shaft 138 suitably journaled in the casing 3. The gear 137^a (Fig. 5) is provided 15 on its outer face with projecting lugs 139 spaced to provide channels 140 for the reception of a pin or roller 141 carried by a gear 20 143 mounted on a shaft 144 journaled in the casing 3. The gear 143 is also furnished with a flange 142 adapted to engage the outer curved surfaces of the several lugs 139 of the gear 137^a. The parts just described 25 constitute an intermittent motion drive of the Geneva type and are so arranged that for each complete rotation of the gear 143, the gear 137^a is turned 90°. The gears 137 and 137^a are of twice the diameter of the gripper 30 operating gears 125 and 125^a so that for each quarter turn of the gear 137^a the grippers are turned through a half revolution.

The gear 143 meshes with an idler gear 145 carried by a stub shaft mounted upon the wall 35 of the casing 3 and this gear 145 meshes with the gear 18 upon the shaft 11. The gear 18 is of the same diameter as the gear 143 and thus through the train of mechanism described, each full revolution of the cam shaft 11 results 40 in a half revolution of the gripper devices.

Pins 146 (Figs. 10^a and 10^b) project laterally from the casing 3 into the paths of the fingers 132^a of the respective gripper devices. 45 These pins are so positioned that at the beginning of each forward movement of the gripper device the fingers 132^a of the uppermost pair of grippers (that is to say those which for the moment are associated with 50 the dies hereafter described) engage the pins 146, (Fig. 10^b) thus opening the gripper jaws and permitting the lace material held by the jaws to drop therefrom.

A shaft 147 (Figs. 5, 5^b and 6 extends 55 transversely across the casing 3 and is provided at an intermediate point with a pinion 148 engaging a rack formed on a sliding bar 149, guided in members 148^a and 148^b of the casing 3. The forward end of the rack bar 60 bears against a lever 149^a pivotally supported on the shaft 103^a and having a cam follower roll 149^b engaging a cam 149^c on the shaft 11. A spring 149^d restores the bar 149 to normal position after actuation by the cam. The 65 shaft 147 is provided near its ends with gear

sectors 150 and 150^a respectively which mesh with sectors 151 and 151^a respectively upon a shaft 152. The sectors 151 and 151^a (Fig. 5^b) are disposed in the planes of rotation of the main grippers and each sector is provided with a surface or element 153 (Figs. 5 and 5^b) adapted to engage the arms 136 of the corresponding movable gripper jaws. At the end of each half rotation of the gripper devices, they occupy substantially the position indicated in Fig. 5^b, the lower jaws being open and the upper jaws closed. After the shuttle has laid the lace material into the open gripper jaws as hereafter described, the cam 149^c actuates the lever 149^a and moves 75 the rack bar 149 thus rocking the sectors and moving the gripper closing arms 136 to close the lower grippers upon the lace material. 80

Removable unit drive

The casing 3 supports a rearwardly extending table 154, (Figs. 1, 4 and 6) provided with an attaching or base portion 155 secured to the rear face of the casing 3 by means of bolts 156 (Figs. 1, 4, and 6). The casing 3 is also provided at its left side with a laterally projecting housing 157 (Figs. 1, 3 and 4) which extends along the left-hand edge of the table 154. A stub shaft 158 is secured to one wall of the housing 157 and carries a duplex 95 sprocket wheel 159 disposed within the housing. Referring to Figs. 2 and 4 the cam shaft 11 is provided at the extreme left-hand end with a sprocket wheel 160, and a sprocket chain 161 transmits movement of rotation from the sprocket 160 to one element of the duplex sprocket wheel 159. 100

Referring to Figs. 1, 4, 19 and 20, a bracket 157^a is mounted upon the left-hand edge of the table 154 and abuts the right-hand side 105 of the housing 157, which is provided with an opening at this point.

The bracket 157^a comprises a boss 167 providing a bearing for a rotary and axially movable shaft 166 (Figs. 4, 19 and 20). The left-hand end of this shaft projects into the housing 157 and is provided with a sprocket wheel 165, about which a sprocket chain 163 passes. This chain 163 engages the second element of the duplex sprocket 159 and transmits movement from the latter to the shaft 166. As the sprockets 160, 159 and 165 are all of the same diameter, the shaft 166 turns at the same speed and in time with the cam shaft 11. In order to take up slack in the chains 161 and 163 I provide adjustable idler pulleys 162 and 164. 110

Referring particularly to Figs. 19 and 20, the shaft 166, which is axially movable in its bearing, is furnished with a circular rack 168 which engages a pinion 169 formed upon a shaft 170 journaled to turn in a suitable bearing in the bracket 157^a. The shaft 170 is furnished with a radial arm 171 at its rear end, and this arm is provided with a sleeve 125 130

172 for the reception of a spring pressed 5 detent pin or handle 173. The inner end of the pin normally engages one of a pair of openings 173^a in the bracket 157^a (one of such openings being shown in Fig. 1) but by retracting the pin 173 from the opening the arm 171 may be swung, thus turning the pinion 169 and thereby moving the shaft 166 axially. The flexibility of the chain 163 10 permits this slight axial movement of shaft 166.

The right-hand end of the shaft 166 (Fig. 20) is furnished with a clutch disk 174 having a transverse slot 175 in its outer face. 15 The bearing boss 167 is furnished with a chamber 176, concentric with the shaft bearing, for the reception of the clutch disk 174 when the shaft is moved to the left.

Tip inserting unit

Referring to Figs. 1 and 3 the upper surface of the table 154 is furnished with parallel ribs or bars 177 and 178 spaced apart to receive between them the lower part of 25 the removable tip inserting unit. This unit comprises an elongate base member 181 (Figs. 1, 22 and 24) which extends from the rear end of the table 154 forwardly to a point adjacent to the rear face of the casing 30 3. Upon the rear portion of this base 181 I mount a cam housing (Figs. 27 and 28) comprising spaced side walls 182 and 183 integrally united by a top wall 184. The side walls are clamped against the edges of 35 the base 181 by means of bolts 184^a. The lower portions of the side walls 182 and 183 are provided with outwardly projecting ribs 179 and 180 (Fig. 27) respectively, which are adapted to have sliding engagement with 40 undercut grooves in the opposed faces of the ribs or bars 177 and 178 respectively.

Referring particularly to Figs. 27, 28 and 29, the side wall 182 is provided with an outwardly projecting part 185 having a bearing 45 for a horizontal shaft 186. This shaft is furnished with a worm gear 187 which meshes with a worm gear 188 on a cam shaft 189 extending transversely across the cam housing. The shaft 189 projects outwardly 50 to the left beyond the wall of the part 185, and is furnished with a clutch disk 190 having a transverse rib 191, which normally engages the slot 175 in the clutch disk 174, 55 previously described (Fig. 20). By retracting the shaft 166 from its normal position, the clutch elements are disengaged, and when so disengaged the tip-inserting unit comprising the base 181 and the parts secured thereto may be slid rearwardly along the guideway 177 and 178 and thus removed 60 as a unit from the machine. In the normal operation of the machine when the clutch elements 174 and 190 are in driving engagement, the auxiliary cam shaft 189 makes one

revolution for each revolution of the main cam shaft 11.

The slot 175 and rib 191 are preferably tapered from one end to the other, or otherwise so shaped that they can only be engaged 70 when in one predetermined relative angular position, thus insuring proper relative timing of the main cam shaft 11 and the auxiliary cam shaft 189.

The forward end of the shaft 186 projects 75 outside of the part 185 and is provided with a gear 192 (Figs. 27 and 29) which meshes with a gear 193 turning on a stub shaft projecting forwardly from the part 185. Forward of the cam housing I mount on the base 181 a second housing 194 (Figs. 21, 22, 23 and 24) comprising a central part having a feed roll chamber 194^a. Casings 195 and 196 are secured to housing 194 at opposite sides of the chamber 194^a. The left-hand casing 195 (Figs. 23, 24 and 27) is furnished with a laterally and rearwardly extending portion 198 which abuts the forward face of the cam housing and encloses the gears 192 and 193. 80

Ribbon feed

The front and rear walls of the chamber 194^a are provided with bearings for the reception of shafts 199 and 200. The shaft 199 is provided at its rear end with a gear 201 95 which meshes with the gear 193 above described. The shaft 200 is furnished at its rear end with a gear 202 which also meshes with the gear 201.

The shafts 199 and 200 are furnished with 100 bushings 203 and 203^a respectively (Figs. 24 and 25) and on these are mounted feed rolls 204 and 204^a respectively. A gear 205 is secured to the roll 204 by means of a pin 206, and a gear 205^a is likewise secured to the 105 roll 204^a.

Each of the shafts 199 and 200 is furnished with a shoulder, as indicated for the shaft 199, at 207 (Fig. 25), and a steel washer 208 bears against this shoulder. A felt washer 209 is 110 interposed between the steel washer 208 and the rear end of the corresponding roll.

Upon the forward end of each of the shafts 199 and 200 I mount a sleeve, as shown at 115 210 (Fig. 25), such sleeves fitting within the bearings in the front wall of the housing 194. The rear end of each sleeve bears against a spring washer 211 which in turn bears against a steel washer 212 splined to the shaft upon which it is mounted. Preferably the washer 208, previously described, also is splined to the shaft. Between the washer 212 and the corresponding gear a felt or other resilient washer 213 is placed. The forward end of 120 each shaft is screw-threaded for the reception of adjusting and locking nuts, by means of which the pressure of the spring washer 211 against the washer 212 may be adjusted.

With this arrangement rotation of either 125 shaft tends to turn the corresponding roller 130

through a friction clutch action, but if the roller meets sufficient resistance it may remain stationary relative to its shaft.

Within the casings 195 and 196 I arrange shafts 214 and 215 respectively and on these shafts mount rolls 216 and 217 respectively. To the roll 216 I secure gear 218 which meshes with the gear 205. Likewise I secure the gear 219 to the roll 217 and cause this gear to mesh with the gear 205^a. The rolls 216 and 204 are thus positively driven in opposite directions, and in the same way the rolls 204^a and 217 are positively driven in opposite directions. The feed rolls of each pair may if desired have roughened or other friction surfaces so as to prevent slipping.

I prefer to mount the shaft 214 in a pair of sliding bearings 220 and 221, and likewise to mount the shaft 215 in sliding bearings 222 and 223. These sliding bearings are suitably guided in the casings 195 and 196 and are urged inwardly by means of springs 224, thus causing the rolls 216 and 217 to engage the corresponding rolls 204 and 204^a with resilient pressure. Preferably, I provide the forward ends of the shafts 214 and 215 with knurled disks 225, by means of which the shafts may be turned by hand if desired.

Ribbon supply

On the top of the housing 194 I mount a hollow standard 194^b (Figs. 21 and 22) preferably provided with a hinged door 226 at its front side, such door having a knob 227, and normally being held in closed position by means of a spring latch 227^a.

This standard 194^b is enlarged laterally at its upper part 228 to provide a pair of chambers 229 and 229^a of substantially circular form. The upper part of this standard comprising the chambers 229 is preferably provided at its front with a hinged door 230 adapted to swing upwardly and furnished with a knob 231 and with a spring catch 232 (Fig. 21). The chambers 229 and 229^a are furnished at their centers with forwardly projecting stub shafts 233 and 234 respectively which are adapted to receive reels 235 and 235^a respectively. These reels may be of the general type employed for holding motion picture film, each comprising a central spool or barrel and side flanges or heads at each end of the barrel. Preferably these flanges are provided with perforations to decrease the weight and to disclose the amount of material wound upon the barrel. In Fig. 22 this material in the form of thin flat ribbon is indicated at 236 and 236^a. Preferably the door 230 is provided with circular openings concentric with the shafts 233 and 234 and of sufficient size to expose the reels to view, and these openings in the door are preferably glazed to exclude dust.

The tip-forming material, which is preferably celluloid, is preferably as above stated,

in the form of a thin ribbon and this ribbon is of a width substantially equal to the length of a single tip, thus differing from the usual practice in which the tip-forming material is of a width double the length of the tip. 70

The two ribbons 236 and 236^a of tip-forming material are drawn off from the reels 235 and 235^a and pass down through the hollow standard 194^b. These ribbons then extend down through channels provided between the outer surfaces of the housing 194 and the inner walls of the casings 195 and 196, respectively, (Fig. 24). These channels, through which the respective ribbons pass, are in the vertical planes of the bites of the 80 pairs of feed rolls 204, 216 and 204^a, 217, respectively, and as the rolls are rotated in the direction of the arrows (Fig. 24) the strips of ribbon are drawn from the reels and pushed downwardly. While I prefer to employ a flat ribbon of celluloid, I contemplate the use of celluloid in other than flat ribbon form, and also the use of other materials than celluloid, and further the employment of independent tip members held in a suitable hopper or receptacle and delivered one by one in any desired manner. 85 90

Slug cutters

At its lower part the housing 194 (Figs. 95 24 and 30) is provided with substantially horizontal shelves 237 and 237^a respectively, projecting laterally from its side walls. Each of these shelves is furnished with a guideway for a reciprocating cutter, the two 100 100 cutters being indicated respectively at 238 and 238^a.

If instead of providing the tip forming material in a strip, it be furnished in independent sections, either solid, flat or round, 105 or tubular or capsule-like, the cutter members may serve merely as gates to determine the delivery of such sections, one by one. These cutters are provided with adjustable bracket members 239 and 239^a which may be 110 fixed in the desired adjusted position relative to the respective cutters by means of screws 240 and 240^a.

The brackets 239 and 239^a are furnished with slots for the reception of the forwardly directed arms 241 and 241^a (Fig. 30) of a pair of bell crank levers pivotally mounted upon the upper surfaces of the shelves 237 and 237^a by means of pins 242 and 242^a, respectively. These bell crank levers have inwardly directed arms 243 and 243^a whose inner ends are received in a transverse slot 244 in a slide bar 245 (Figs. 24 and 30) which is seated in an elongate groove or slot 246 in the upper surface of the member 181. The slide bar 245 is retained in position by means of one or more straps 247 flush with the upper surface of base 181. 120 125

The slide bar 245 is furnished with a socket opening 248 near its rear end which receives 130

the lower end of an actuating lever 249 (Figs. 27 and 28). This actuating lever is mounted upon a shaft 250 which has fixed thereto oppositely directed arms provided respectively with cam follower rolls 251 and 251^a.

5 These rolls engage cams 253 and 254 (Fig. 28^a) respectively mounted upon the cam shaft 189 above described, one of these cams moving the slide bar 245 positively in one direction and the other cam moving the bar 10 positively in the opposite direction.

15 Adjacent to the inner edges of the shelves 237 and 237^a (Figs. 24 and 30) blocks 255 and 255^a respectively are arranged. These blocks are furnished with slots 256 and 256^a respectively for the passage of the ribbons 236 and 236^a respectively. These slots extend down to the plane of the upper-surfaces of the cutters 238 and 238^a and below this 20 plane the blocks 255 and 255^a are provided with transverse slots 257 and 257^a respectively of a vertical height equal to that of the cutters and of a front to rear length substantially equal to the width of the ribbons of 25 tip-forming material. These slots 257 and 257^a constitute guideways for the inner ends 30 of the cutter, and the upper wall of each slot cooperates with its cutter to sever that portion of the respective ribbon which projects down into the guideway.

35 As shown in Fig. 30 the slots 256 and 256^a in the blocks 255 and 255^a are preferably oblique to the axes of the cutters so that a ribbon passing through one of these slots is slightly twisted. Thus as the square edged cutter moves along its guideway in the block, it first engages the ribbon near one edge and so severs the latter by a shear cut. The lower surfaces of the guideways 257 and 257^a constitute stops for the ribbons, against which 40 the ribbons are fed by the action of the feed rolls. At each actuation of the cutter a tip-forming slug of celluloid of uniform width is cut from the ribbons and moved inwardly along the slot 257 and 257^a by the corresponding cutter.

Tip inserting instruments

45 The lateral faces of the base member 181 are furnished with elongate slots 258 and 258^a (Fig. 24) for the reception of the tip inserting instrumentalities. Within the slots 258 and 258^a I arrange elongate dilating needles 259 and 259^a (Figs. 30 to 34). Each 50 of these needles is provided throughout the greater portion of its length with a slot 259^b (Fig. 32) in its outer vertical face. Each needle likewise is sharpened at its forward end to form a flattened point 260^a to facilitate its entrance into the end of a tubular lace. The point of the needle is preferably 55 furnished with a resilient cover plate 260^b secured to the main body of the needle by means of pins or rivets 261^a (Fig. 33). The plate 260^b covers the groove 259^b at the end

or point of the needle but can spring away from the opposed surface of the needle proper to permit passage of a slug of tip-forming material.

60 Near their rear ends the needles are furnished at their inner faces with lateral projections 262, 262^a respectively. The base member 181 is slotted as indicated at X to accommodate these lateral projections of the needles, the slots being of sufficient length 65 to permit the desired longitudinal movement of the needles. The lateral projections of the needles are furnished respectively with sockets 263 and 263^a (Fig. 30) and these sockets receive the lower ends (Figs. 27 and 28) of levers 264 and 264^a respectively which are fixedly secured to a shaft 265 whose ends are journaled in the walls 182 and 183 of the cam shaft housing. The shaft 265 is provided with divergent arms carrying cam follower rolls 266 and 267 respectively. These 70 follower rolls engage cams 268 and 269 mounted on the cam shaft 189. One of these cams moves the needles positively in one direction and the other cam positively restores 75 them to initial position.

75 The slots or grooves 229^b in the outer edges of the needles receive elongate plunger bars 269 and 269^a respectively (Figs. 30 to 34). The forward ends of these plunger bars are 80 preferably provided with grooves 271 respectively (Figs. 32, 33, and 34) for the reception of the free extremities of the flexible cover members 260^b of the needles. These 85 grooves 271 are widest at their outer ends 100 and gradually taper in width and depth toward the rear end of the plunger bars.

90 The plunger bars are provided respectively upon their outer sides with lateral projections 272 and 272^a respectively and these projections are furnished with sockets 273 and 273^a for the reception of the lower ends of a 105 pair of levers 274 and 274^a (Figs. 27 and 28) secured to shaft 275 journaled at its opposite ends in the walls 182 and 183 of the cam 110 shaft housing. The shaft 275 carries a pair of arms provided respectively with cam follower rolls 276 and 277, which engage cams 278 and 279 respectively on the shaft 187. One of these cams moves the plunger bars 115 in one direction and the other cam moves them in the other direction.

Lace holders

120 Below the slots 258 and 258^a in the base member 181 (Fig. 24) are other slots adapted to receive longitudinally movable slide bars 280 and 280^a disposed immediately below the respective needles. The forward end of the base 181 is provided with an extension (Figs. 125 6, 22, 30 and 33) providing a table-like surface 181^b disposed in a plane slightly below the upper surface of the main body of the member 181. The slide bars 280 and 280^a are provided respectively at their forward ends 130

with holders or brackets 283 and 283^a (Figs. 30, 30^a and 31) which project up above the surface of the table 181^b and are provided with overhanging portions 284 providing recesses 282 of a vertical depth substantially equal to the width of the lace forming material. Each of these holders or brackets carries a flat spring 285, preferably folded or bent at the point 286 (Fig. 30) to provide 10 a resilient lace-engaging member 287 disposed within the recess 282.

Just in front of the housing 194 and at opposite sides of the table 181^b I provide the positioning or abutment blocks 288 and 288^a respectively. These blocks are furnished respectively with chambers 289 and 289^a for the reception of absorbent material M (Figs. 30 and 31) and each of these chambers is provided with a slot 290 in its inner wall (Fig. 20 31). The vertical depth of this slot is substantially equal to the width of one of the tip-forming slugs and its length from front to rear is substantially equal to the length of a lace tip. These slots are so disposed as 25 to register with the recess 282 in the corresponding holder or bracket 283 or 283^a when the holder slides 280 and 280^a are moved rearwardly (Fig. 30^b).

The rear ends of the holder slide bars 280 30 and 280^a are furnished with sockets 293 and 293^a respectively, for the reception of the lower ends of the levers 294 and 294^a (Figs. 27 and 28) secured to shaft 295, journaled at its opposite ends in the walls 182 and 183 35 of the auxiliary cam shaft housing. The shaft 295 is provided with a pair of arms 296 furnished respectively with cam follower rolls 297 and 298. These follower rolls 297 and 298 engage cams 297^a and 298^a carried 40 by the cam shaft 187. One of these cams thus moves the slide bars 258 and 258^a in one direction while the other cam moves the bars in the opposite direction. When these bars are in their forward or normal position they 45 are disposed as shown in Fig. 30, but when in their rearmost position they are so disposed that the recesses in the brackets 284 and 284^a register with the slots 290 as indicated in Fig. 30^b.

50 The forward edges of the blocks 288 and 288^a are preferably beveled or rounded as shown at 292 (Fig. 31) to provide guide surfaces for the lace material and these beveled or rounded surfaces merge into vertical lace 55 positioning surfaces 291 and 291^a.

Lace cutter

On the forward end of the table 181^b I 60 mount a bracket 299 (Fig. 30) which supports the fixed or ledger blade 300 (Figs. 30, 31, and 35) of a lace cutting shears device. This shears device is placed midway of the width of the table 181^b and comprises 65 the movable cutter or blade 301 mounted on the pivot 301^a and held in operative contact

with the fixed blade 300 by means of a spring coiled about the pivot pin. The blade 301 is provided with an actuating arm 301^b (Fig. 35) which projects through a slot 301^c in the table 181^b and into a socket opening 301^d in 70 a slide bar 301^e. This slide bar is disposed within a slot 302 (Fig. 35) in the underside of the base 181 and is retained in position in the slot by means of straps 303 similar to the straps 247 above referred to.

The slide bar 301^e is furnished with a slot or socket 304 near its rear end and the base member 181 is provided with an elongate opening 305 (Fig. 30) to permit the lower end of the lever 306 (Figs. 27 and 28) to enter the socket 304. The lever 306 is mounted upon a sleeve 307 turning on shaft 250 and carrying a pair of oppositely directed arms provided respectively with cam follower rolls 308 and 309. These cam follower rolls engage cams 310 and 311 respectively on the cam shaft 189. One of these cams thus moves the slide bar 301^e forwardly to close the shear blade 301 while the other cam moves the slide in the opposite direction to open the shears. 90

Solvent feed

The blocks 288 and 288^a are furnished with laterally and rearwardly directed members terminating in screw-threaded nipples 313 and 313^a (Fig. 30). These nipples are furnished with passages communicated with the chambers 289 and 289^a in the blocks and the nipples are connected by means of pipes 314 and 314^a (Figs. 1 and 3) with a hollow support 315 (Fig. 21) for a fluid supply reservoir. This support 315 is secured in any desired manner to the rear surface of the cam housing and, if desired, may be provided with brace members 316 extending to the upper part of the standard 194. 100

While the support 315 may carry any suitable type of reservoir for supplying the solvent fluid, I prefer to employ the reservoir shown in Fig. 26, consisting of an inverted glass jar 317, having a cover 318 provided with a tubular nose portion 318^a adapted to fit down into a socket in the support 315. The tubular nose portion 318^a is preferably furnished with a valve of any suitable type adapted to prevent the escape of fluid but which is provided with a nose 320 adapted to engage the bottom of the socket in the support 315 and thereby to open the valve, permitting the fluid to pass from the container 317 down into the support 315 and thence through the pipes 314 and 314^a to the chambers in the blocks 288 and 288^a where it moistens the absorbent material within such chambers. Preferably the container 317 is 115 furnished with a tube 321 for admitting air. 120

Tip shaping die

Referring more particularly to Figs. 3, 6, 16 and 17 the part 102 of the casing 3 supports 125

a table 322 whose rear end overhangs the forward end of the table 181^b. At opposite edges of the table 322 I provide curved guide members 323 and 323^a respectively (Fig. 3). These guide members are preferably concentric with the axis of the shaft 99 and are furnished with slots 324 and 324^a respectively for the accommodation of the auxiliary gripper devices 106, 106^a.

10 The table 322 furnishes a support for a reciprocating die block 325. This block is provided with a bracket 326 to which I attach two movable die members 327 and 327^a (Fig. 16) respectively which engage the upper horizontal surfaces 328 and 328^a respectively of a normally fixed die member 329. Preferably the member 329 is furnished with a guide or spacer 329^a which is disposed between the movable die members 327 and 327^a.

15 20 The forward end of the die member 329 is furnished with a part 330 (Fig. 17) which is adapted to reciprocate in a suitable opening in a guide bracket 331 (Figs. 3 and 17) depending from the rear edge of a plate 332 secured by bolts 333 to the upper part of the casing 3. The part 330 of the die member 329 is provided with screw-threaded sockets for the reception of the ends of a pair of guide bars 334. At their forward ends these guide bars pass through guide openings in a thick plate 335 which is attached by means of bolts 336 (Fig. 17) to the bracket member 331. Coil springs 337 encircle the guide rods 334 and normally retain the die member 329 in its rearmost position as determined by the heads 334^a of the rods 334. However, when the die member 329 is subjected to sufficient pressure it may yield slightly, compressing the springs 334.

25 30 Preferably the guide rods 334 are furnished with radial ribs or fins 338 and the connecting bolts 336 are likewise provided with fins 339 in order that heat received from the die proper may be radiated as rapidly as possible.

The forward edges of the movable die plates 327 and 327^a are furnished with substantially semi-circular grooves 340, while the relatively fixed die member 329 is provided with grooves 341 having substantially semi-circular inner walls, but these grooves are sufficiently deep to permit entrance of the forward edges of the die plates 327 and 327^a.

The die member 329 is furnished with a transverse opening or chamber 342 for the reception of suitable heating elements 343. These heating elements, one of which is shown in section in Fig. 18, may be of any usual type employed in electrical heating and are provided with suitable lead wires for connecting them to a source of electric current.

The die supporting block 325 is preferably slotted, as indicated at 344, throughout the major part of its length so as to radiate heat as rapidly as possible, and the tongues 344^a separating these slots are furnished at their

rear ends with openings 345 (Fig. 16) for the reception of a pivot pin 346 (Fig. 6) by means of which these tongues are connected to corresponding series of links 347 which in turn are connected at their rear ends to a pivot shaft 348, carried by a bell crank lever pivotally supported upon a transverse shaft 349 mounted in the casing 3. The lever is provided with an arm having a cam follower roll 350 which is adapted to engage a cam 352 (Fig. 2) on the main cam shaft 11. This lever also has an arm 351 adapted to engage a second cam 353 on the same shaft. Preferably the pivot rod 348 is provided with a piece 348^a adapted to engage a stop 348^b and, if desired, a spring 348^c may encircle the rod 348^a to assist the cam 353 in returning the removable die to its normal position.

Modified construction

Referring to Figs. 37 to 39 inclusive, I have illustrated a modified arrangement for presenting the lace material to the tip-inserting means and the dies, it being understood that in other respects the machine is generally similar to that above described.

In Fig. 37 the member 154 of the casing 3, (not otherwise shown) supports the base member 181 of the tip-inserting unit (the other parts of which are omitted) in the same way as in the previously described construction. The shears for cutting the lace material are of the construction already described.

In this modified arrangement I provide a rotary shaft 354 journaled at one end in a member 355 suitably secured to the part 154. The opposite end of the shaft 354 may be journaled in any suitable part of the machine frame and may be considered as the substantial equivalent of the shaft 99 previously described. This shaft 354 is driven by the Geneva mechanism above described, but is so geared as to turn 90° at each step instead of 180° as in the first described arrangement.

The shaft 354 carries the hub 356 of a turret 357, the hub 356 being splined or otherwise secured to the shaft. The turret 357 supports four pairs of gripper devices indicated in Fig. 38 at 358, 359 and 361 respectively. A pair of hooks is interposed between each adjacent pair of grippers, these hooks being designated 362, 363, 364 and 365 respectively.

The grippers are of substantially the same construction as the main grippers above described and illustrated in Figs. 10 and 10^a. Each gripper comprises a fixed jaw and a movable jaw and is furnished with an arm 366 (Fig. 38) by means of which the jaws are opened, and another arm 366^a by means of which the jaws are closed.

Each gripper of a pair comprises the holder 368 secured to a shaft 369 suitably journaled in brackets carried by the turret.

Each shaft 369 is provided with an arm 370 connected to a spring-pressed plunger 371 guided in a suitable guideway in the turret; each plunger 371 is connected at its opposite end to a lever 372 pivotally supported upon the outer side of the turret. The inner end of each lever 372 engages a pin 373 sliding in a suitable guideway in the turret and the pins 373 are adapted, in certain angular positions of the turret, to engage the ends of actuating bars 374 sliding in guideways in the members 154 and 355. These slide bars are actuated at the proper intervals to move the levers 372 and thus to swing the gripper members 368 inwardly so that the open jaws of the gripper may be in a position to receive the lace material as it is laid as indicated at L (Fig. 37) across the lower blade of the shears.

20 The member 154 is provided with a guide for the reciprocating die block 325^a. This block is secured to a link 347^a pivotally connected to a lever mounted upon a shaft 349^a, these parts corresponding to the parts for 25 actuating the movable die block previously described. In this case the lever mounted upon the shaft 349^a is connected by a pivot 377 to an eccentric strap 378 embracing the eccentric 380 mounted on the cam shaft 11^a.

30 The normally fixed member 329 of the die is yieldably supported in the same way as the corresponding member previously described by means of a plate 381 (Figs. 37 and 39). This plate 381 is attached by means of bolts 382, 383 and 384 to a convenient part of the frame. Preferably, and as here shown, the plate 381 is provided with guides for the supporting pins 385 and 386 of two sets of dies. The dies shown in the section of Fig. 37 are 35 those corresponding to the pins 386, but I prefer to provide a second set of dies at 90° distance from the first dies. This second set of dies will be substantial duplicates of the set illustrated and may be actuated by the 40 same mechanism and in time therewith.

45

Operation

The operation of the machine is substantially as follows, reference being had first to 50 Figs. 40 to 43 inclusive.

It is assumed that the shuttle 90 has been stopped at the extreme left-hand end of its path of travel. The handle 40 is in its mid-position, the worm gear 10 (Fig. 2) is running idly on the cam shaft 11, the latter being held in predetermined stopped position by means of the stop dog 27; the lace-cutting shears comprising the blades 300 and 301 are open; and the main and auxiliary grippers 55 have just completed the transfer of a pair of lace ends from the tip-inserting devices to the dies. The tip-inserting needle with its plunger is fully retracted; the holders 283 and 283^a are in their normal inoperative position; the dies are open, the slug cutters 238

and 238^a are retracted; the ribbons 236 and 236^a of tip-forming material have been fed downwardly until their lower ends abut against the bottom walls of the slots 257 and 257^a (Fig. 24); and the receptacle 317 has been supplied with a celluloid solvent, for example, acetone or acetone mixed with alcohol, which has flowed down into the chambers 289 and 289^a containing the absorbent material.

To start the machine the operator swings the handle 40 to the right, as viewed in Fig. 3, thus disengaging the detent 50 and permitting the shaft 35 (Fig. 12) to move to the right, releasing the dog 27 and permitting the spring 24 to throw the drive clutch into engagement, thereby clutching the worm gear 10 to the cam shaft 11. The cam shaft immediately begins to turn and through the gear connections above described actuates the sprocket chain 59, thereby turning the pulley 76 and thus pulling upon the cord 93 and thereby moving the shuttle 90 along its path. As the pulley rotates, the traverse guides 83 lay the cord upon the pulley rim in proper position to insure its free delivery.

The sequence of operations is briefly as follows, referring to the diagrammatic views (Figs. 41 to 43) in which figures, for convenience in description, the auxiliary grippers have been omitted. Referring first to Fig. 40, the main gripper device 127 is shown as provided at its opposite ends with the grippers G¹, G² while the other main gripper device 127^a is provided with the grippers g¹, g² at 100 its opposite ends. For convenience, the shaft which carries the grippers and the anchor devices 119 and 120 has been shown as a single shaft which is designated 99^b. The anchor device 119 has the arms A¹, A², while the anchor device 120 has the arms a¹, a².

In the position shown the shuttle 90 is just completing its movement toward the right, the gripper jaws G¹ and g¹ are open and the new run of lace material extends around the anchor arm A², thence through the open jaws of the grippers G¹ and g¹, across the arm a¹ and to the shuttle. A length of lace material, which resulted from a prior movement of the parts, extends from the arm A² into the closed gripper G², and at this time is held within the left-hand die indicated at D¹, this latter length of lace being designated as lace No. 1. After the shuttle has laid the new length of lace in the jaws of the grippers G¹ and g¹ and while the shuttle still continues its movement to the right, the grippers G¹ and g¹ close, the shears 300, 301 sever the lace material intermediate the grippers, and the tip-inserting means, not shown in the diagram, introduces a slug of tip-forming material into each of the several ends of the lace material.

The shaft 99^b now makes a half turn, bringing the parts into the position shown in Fig. 41. During the early part of this movement

the dies D^1 drop the completed end of the lace No. 1 so that the latter hangs freely down as shown in Fig. 41. At the completion of this half rotation the other end of lace No. 1, held in the gripper G' has been placed in the die D^1 , while the end e^1 of lace No. 2 has been placed in the die d^2 . During this rotation the shuttle 90 has made its journey toward the left and has laid a new length of lace material in the open jaws G^2 and g^2 , this material extending around the arm a^1 and thence through the jaws to the shuttle. The dies now form the tips upon the lace ends held in the jaws G^1 and g^1 while at the same time the tip-inserting means inserts slugs of celluloid in the ends e^2 e^3 of the lace material which has just been severed by the shears S. The shaft 99^b now makes a further half rotation with the result indicated in Fig. 42. During the early part of this rotation the grippers G^2 and g^2 open so that lace No. 1 is dropped completely from the machine, while the end e^1 of lace No. 2 is also dropped and hangs freely down from the gripper g^2 . The open grippers G , g^1 now receive the new run of lace material which is laid therein as the shuttle travels toward the right, this lace material extending around the arm A^2 of the anchor 119 and thence through the jaws and across the cutter. The dies and tip-inserting means now operate again and the shaft 99^b makes a further half turn with the result shown in Fig. 43 wherein the grippers G' and g' have dropped the ends which they held, thus releasing the end e^2 of lace No. 3, and dropping lace No. 2 completely from the machine.

This sequence of operations thus continues with the result that a completed lace is dropped from the machine at each reciprocation of the shuttle.

For a more specific description of the mode of operation I will now refer to Fig. 36 which diagrammatically represents one complete revolution of the cam shaft 11. In this figure the character A represents that point in the rotation of the cam shaft which has been selected as indicating the beginning of the operation. Prior to this point, the shuttle has started from the left-hand end of its path of travel at a point in the cam movement indicated at a and at this time has not yet reached the position of the auxiliary and main grippers. The point b indicates the end of the previous movement of the main grippers for transferring the lace ends from the inserting point to the dies and at substantially this same point in the operation the auxiliary grippers, as indicated at c begin to recede to their normal position which they reach at a point indicated at g . Since the main gripper devices are duplex and are moved forward continuously in the same direction, it is evident that while the grippers at the dies are dwelling (from the point indicated at b ,

throughout the remainder of the operations to be described) the corresponding grippers at 180° distance are also dwelling in position to receive a new stretch of lace material.

At about this time the slug cutters 238 and 238^a (Fig. 24) are moved inwardly, thus cutting off the projecting lower ends of the celluloid ribbons 236 and 236^a. Since these ribbons are of the width corresponding to the length of a lace-tip, the slugs thus removed are of the desired length to constitute a tip and the cutters 238 and 238^a are of a proper thickness to cut a slug of the desired width. These cutters are moved inwardly after cutting off the slug until they push the slug into the groove 259^b of the adjacent needle and preferably the slug cutters dwell in this inward position, from the point indicated at e to the point indicated at j in the cam diagram, thus holding the slugs in proper position within the needles.

At some proper point, for example, the point f in the diagram, the dies begin to close upon the tips disposed within them and slightly before they reach their limit of travel they exert sufficient force upon the enclosed lace material and tip to cause the normally stationary die to yield slightly against the action of its springs 334. The compression to which the lace material is subjected is thus of resilient character, avoiding any overstrain of the parts or the necessity for extreme accuracy in the formation of the die-actuating cam.

Immediately after the auxiliary grippers have returned to their normal position, as indicated at g in the diagram, the shuttle passes the position of these grippers and also passes the main grippers, which at this time stand open in receiving position. As above described, the lower part of the shuttle arm 95 is bent at the point 98 so that its guide rolls 96 and 97 may lay the lace material accurately into the open jaws of the main grippers and in the path of movement of the auxiliary grippers, the lace material also extending across the edges 292 of the blocks 288 and 288^a (Figs. 30 and 31) as indicated at L' in Fig. 30, from which position it slips down against the surfaces 291 and 291^a and between the shear blades 300 and 301. At about this time in the operation, the shaft 147 is actuated to close the jaws of the main grippers upon the lace, whereupon the cutter-actuating cam begins to operate at the point i (Fig. 36) to close the cutters and sever the lace held by the main grippers and which has been drawn between the jaws of the auxiliary grippers.

The slug cutters now begin to retract at the point j (Fig. 36) and continue to retract until they reach their normal position as indicated at k . During this movement the holders 283 and 283^a begin to advance to their operative position, the point of advance being indicated at m in the diagram and at sub-

stantially the same time, as indicated at *l*, the plungers 269 and 269^a begin to advance toward the tips of the needles. The completion of the cutting operation is indicated at *n* in the diagram and after a slight dwell the cutters again open as indicated at *u*.

The advance of the plungers continues until at about the point *q* in the diagram the plunger has moved the slug *S* (Fig. 30) of tip-forming material up into the point of the needle. During this movement of the plunger the holders 283 and 283^a have been advanced, beginning at the point *m* until at the point *o* in the diagram the holders are disposed substantially opposite to the blocks 288 and 288^a. During this movement of the holders, the springs 287 engage the severed ends of the lace material and turn such ends at right angles to their former direction until the ends occupy the positions *L*⁴ and *L*⁵ in Fig. 30. These ends are thus held firmly but resiliently against the inner faces of the blocks 288 and 288^a by the pressure of the springs 287 and it may be noted that these end portions of the lace are disposed against the apertures 290 in the blocks 288 and 288^a so that they absorb some of the liquid contained in the absorbent material *M*.

As the holders reach this operative position, holding the lace ends firmly between them and the inner surfaces of the blocks 288 and 288^a, the dilating needle begins to advance from the point *p* in the diagram (substantially coinciding with the point *o* at which the movement of the holders ceases).

At the same time the plunger within the needle begins an accelerated movement at the point *q* and moves at the same rate as the needle so as to maintain the slug of celluloid within the point of the needle. The needle thus continues to advance until its tip has entered within and distended or dilated the end portion of the tubular lace which, as above stated, is firmly held between the spring of the holder and the adjacent wall of the block which carries the absorbent material. This position of the needle is indicated in Fig. 33. The end of the advance movement of the needle is indicated at *r* in the diagram and the needle dwells for a very short period and then begins to retract at the point *s*. The plunger continues its forward movement during the dwell period of the needle, terminating such movement at the point *t*. During this additional movement the slug is pushed forwardly from out the point of the needle. During the dwell of the plunger, between the points *t* and *u* in the diagram, the needle retracts beginning at the point *s* and continuing to the point *v*. This retraction of the needle, as indicated in Fig. 34, leaves the slug within the end of the lace, the plunger dwelling in contact with the slug until the needle has been completely removed from the lace. Thereupon, at the point *w*

the plunger begins to retract toward its normal position. At about the same time the holders begin to retract, as indicated at *w*, permitting the lace ends with their inserted slugs to return nearly to their original position by reason of the elasticity of the lace material and the tension to which it is subjected.

At about the time that the plunger begins to retract, the auxiliary grippers, as indicated at the point *y*, begin to swing to carry the lace ends from the inserting position up to the position where they may be operated upon by the dies. At substantially the same time the main grippers begin to swing, and during the early part of this movement the grippers which have been associated with the dies are opened, thus dropping the ends which have been completed, while the opposite ends of the gripper devices, which are closed upon the ends of the lace having the slugs inserted therein, swing with the auxiliary grippers to place these new ends in operative position within the dies.

During the operation of the dies and the tip-inserting means, the shuttle has completed its movement to the right and has begun to travel toward the left and, as the new cycle of operations begins, the auxiliary grippers are restored to normal position leaving the lace ends lying in the dies and held by the main grippers while the opposite ends of the main gripper devices are opened ready to receive the new length of lace material as the shuttle passes them.

During the insertion of the tip-forming slug within the end of the lace, solvent material is permitted to moisten the lace material which encloses the slug and when this moistened lace material with its enclosed slug is subjected to the action of the heated dies, the slug is very firmly embedded within the interstices of the lace fabric and brought into substantially cylindrical form, thereby forming a tip which so firmly adheres to the lace material that it is substantially impossible to remove it by mechanical means.

It may be noted that the rolls (Fig. 24) for feeding the tip-forming material are adapted to feed much more material than is cut off at each operation of the machine, but due to the fact that the rolls are driven through a friction clutch arrangement, as shown in Fig. 25, they begin to slip as soon as the predetermined length of ribbon has been advanced. It is thus unnecessary to employ any nicely adjusted timing mechanism for advancing or measuring the ribbon, since the amount of ribbon advanced at each operation is determined solely by the thickness of the cutter or, in other words, by the vertical depth of the recess 257 or 257^a across which the ribbon advances, and when the ribbon strikes the lower wall of

this recess and is positively stopped, the feed rolls cease to function since they slip relatively to their driving shaft. At the same time a proper and positive feed of the celluloid is assured at all times.

The supply of celluloid may be replenished at any time by opening the cover 230 and placing a fresh reel upon the reel-supporting shaft and the lace material may be supplied to the shuttle from any suitable source, not shown, and may be guided to the shuttle eye in any suitable manner.

The machine continues to operate as above until the operator decides to stop it, whereupon he swings the handle 40 to the left as viewed in Fig. 3, thus moving the shaft 35 to the left until it is locked by the detent 50. This movement causes the dog 27 to swing down into the path of the ears 25 and 26, thus first stopping the clutch spider, thereby disengaging the gear 10 from the shaft 11 and then positively stopping the cam shaft 11. In this way the cam shaft is always stopped at a given position which may be selected as desired to leave the parts, when the machine is stopped, at the most suitable point for inspection or adjustment.

The cycle of operations of the modification shown in Figs. 37 to 39 and 44 is slightly different from that above described. In these views, G^e indicates a guide through which the lace material L passes and this material is indicated as extending from this guide, in front of the upper hook 362, across the grippers 358, about the upper hook 362, thence in a bight of approximately a lace length about one of the anchors and back around the lower hook 363, then through the grippers 359 around the upper hook 364, then in the form of a bight around one of the anchors and back around the lower hook 364, then through the grippers 360 and around the lower hook 365 from which one end of a completed lace depends.

It being assumed that the parts are in this position, a suitable shuttle or looper S' or any other suitable device, for example the finger of the operator, is brought against the run of lace extending from the guide G^e to the upper hook 362 and draws off lace material from the supply through the eye G^e to form a bight B (Fig. 44) of substantially lace length. The looper S' now drops this bight about one of the anchors and the shaft 354 makes a quarter turn. As the shaft 354 turns, the anchor device turns with it, thus keeping the bight B of lace material taut. The lower hook 362 engages the left hand limb of this bight and carries it over to the right, causing material from the eye G^e to be drawn across the open grippers 361 which, at the end of this quarter rotation, occupy the position 358. These grippers 361 now close and the lace material between them is severed by the shears and the tip-inserting means places

a slug of celluloid in the freshly severed ends of this material.

While this operation is being performed, the looper S' is again drawing off a loop from the eye G^e , the turret now makes another quarter rotation in which the above operations are repeated and which carries the tips just supplied with slugs of celluloid down to the position 359 at which one set of dies is located. Here these ends are subjected to the pressure of the heated dies while, at the same time, slugs of celluloid are being inserted at the position 358 in a new pair of ends. The turret makes another quarter turn, bringing the tips which have already been partially formed by the first set of dies down to the position 360 where they are subjected to a further compression which finishes these tips. During this finishing operation a preliminary compression is occurring at the point 359, and slugs are being inserted at the point 358. At the beginning of the next quarter turn the grippers at the point 360, and which hold completed tips, are opened, thus dropping these tips, the left-hand tip being that belonging to a fully completed lace, while the other end of the lace to which the right hand tip belongs is held in the lowermost of the grippers 359.

The sequence of operations is thus generally similar to that above described with respect to the first construction, except that in this arrangement the lace tips are subjected to two operations of the heated die, thus producing a somewhat better finish and more intimate union of the celluloid with the lace fabric.

While certain desirable embodiments of mechanism have been illustrated for practicing the process herein described, I wish it to be understood that the process may be carried out by other means and that the apparatus here disclosed may be varied in dimensions and relative arrangement of parts and that equivalent arrangements may be substituted for those here described, without departing from the spirit of the invention.

I claim:

1. That process of tipping laces which comprises as steps measuring off a length of lace material from a supply, severing said length at substantially its middle point, deflecting the severed end portions out of line with the remainder of the material, and applying stiffening material to said deflected portions.

2. That process of forming tipped laces in succession from a length of lace material which comprises as steps applying stiffening material to one end portion of a length of lace material, severing said lace material at a predetermined distance from said end thereby to form a lace, and while applying stiffening material to both ends of the lace material resulting from such severing operation, subjecting the first-named end of the lace ma-

terial with its stiffening material to pressure.

3. That process of tipping laces which comprises as steps measuring off a length of lace material, cutting said length at an intermediate point whereby to form portions of two laces, simultaneously applying stiffening material to each of the ends resulting from the cutting operation, measuring off a second length of lace material, said second length being continuous with one of the two laces aforementioned, cutting said second length at an intermediate point thereby producing two new ends, and while simultaneously applying stiffening material to said new ends, subjecting the first-named ends to pressure.

15 4. That process of tipping laces which comprises as steps laying a substantially straight run of tubular lace material in a predetermined position, severing said run at an intermediate point thereby producing two new ends, deflecting each of said new end portions so as to cause it to lie at an angle to the original run of material, and simultaneously inserting tip-forming material within each of 25 said deflected end portions.

30 5. That process of tipping laces which comprises as steps laying a run of tubular lace material in a predetermined position, severing said run at an intermediate point thereby producing two new ends, bending said end portions to cause them to lie substantially parallel to each other, dilating said end portions, and simultaneously inserting tip-forming material in said end portions.

35 6. That process of tipping laces which comprises as steps laying a substantially straight run of tubular lace material in a predetermined position, severing said run at an intermediate point thereby producing two new ends, bending said end portions to cause them to lie substantially parallel to each other and perpendicular to the original run of lace material, inserting tip-forming material in each of said end portions, and subsequently subjecting each of said end portions to pressure.

45 7. That process of tipping laces which comprises as steps laying a run of tubular lace material in a predetermined position, severing said run at an intermediate point thereby producing two new ends, simultaneously deflecting each of said end portions to cause it to lie substantially at right angles to the original run of lace material, simultaneously dilating each of said deflected end portions, 55 and simultaneously inserting tip-forming material into each of said dilated end portions.

60 8. That process of tipping laces which comprises as steps laying a substantially straight run of tubular lace material in a predetermined position, severing said run at an intermediate point thereby producing two new ends, bending said ends in opposite directions to cause them to lie substantially parallel, gripping said end portions with resil-

ient pressure, dilating each of said end portions, simultaneously inserting a slug of tip-forming material in said dilated end portions, permitting said end portions to collapse upon the inserted slugs, and subsequently subjecting said end portions to pressure.

70 9. That process of tipping laces which comprises as steps measuring off a length of tubular lace material, severing said length whereby to form portions of two laces, simultaneously introducing tip-forming material into each of the ends resulting from severing the material, measuring off and severing a second length, and while introducing tip-forming material into the last-formed ends, subjecting the first-named ends with their tip-forming material to pressure.

75 10. That process of tipping laces which comprises as steps measuring off a length of tubular lace material, cutting said length whereby to provide portions of two independent laces, introducing a slug of celluloid into each of the ends resulting from said cutting operation, measuring off a second length of material, said second length being continuous with one of the two laces aforementioned, cutting said second length to form two new ends, and while introducing slugs of celluloid into said last-named ends, subjecting the first-named two ends with their slugs to pressure.

80 11. A machine of the class described having means for introducing tip-forming material into the end of a piece of tubular lace-forming material, said means comprising a dilating needle comprising a shank having an axially extending channel and a point having a chamber forming a continuation of said channel, means for delivering tip-forming material into said channel, means for advancing the needle to introduce its point into the end of the lace material, means for pushing the tip-forming material along the channel into the needle point disposed within the lace material, and means for retracting the needle while holding the pushing means relatively stationary whereby to eject the tip-forming material from the needle tip into the end portion of the lace material.

85 12. A machine of the class described having means for introducing tip-forming material into the end of a piece of tubular lace-forming material, said means comprising a dilating needle comprising a shank having an axially extending channel and a point having a chamber forming a continuation of said channel, means for delivering tip-forming material into said channel, a plunger movable longitudinally of said channel, and means for advancing the needle to introduce its point into the end portion of the lace material and for thereafter retracting the needle, and means for advancing the plunger relatively to the needle while the point of the latter is disposed within the lace material whereby to push the tip-forming material

- into the point of the needle and for holding the plunger relatively stationary during the retraction of the needle whereby to eject the tip-forming material from the needle point 5 into the lace material.
13. A machine of the class described having means for introducing tip-forming material into the end of a piece of tubular lace-forming material, said means comprising a 10 dilating needle comprising a shank having an axially extending channel and a point having a chamber forming a continuation of said channel, means for delivering a slug of tip-forming material into said channel, a 15 plunger movable longitudinally of the channel, cam means for advancing the needle point into the end of the lace material, and for thereafter retracting the needle point from the material, and cam means for advancing the plunger relatively to the needle 20 to push the tip-forming material into the needle point and for thereafter retracting the plunger, said cam means causing the plunger to dwell in advanced position during retraction of the needle to eject the tip-forming material from the needle point.
14. A machine of the class described comprising means for positioning a substantially straight run of flat tubular lace material, 25 means for transversely severing said run to provide an end portion open at its extremity, means for bending at least one of the severed end portions of the lace material to cause it to lie at an angle to its original position, and means for introducing a flat slug of tip-forming material into the open extremity of 30 said end portion while disposed at said angle.
15. A machine of the class described comprising means for positioning a run of lace 35 material, means for severing said run, means for bending at least one of the severed end portions of the lace material to cause it to lie at an angle to its original position, means for clamping said end portion in its new position, and means for applying tip-forming material to said end while so clamped.
16. A machine of the class described comprising means for positioning a run of tubular lace material, means for severing said 40 run at an intermediate point, means for turning at least one of the severed end portions of the lace material into a position substantially at right angles to its original position, means for resiliently clamping said end portion in its new position, means for dilating said clamped end portion, and means for inserting tip-forming material into said clamped and dilated end.
17. A machine of the class described comprising means for positioning a run of tubular lace material, means for severing said run 45 at an intermediate point, means for turning the severed end portions of said run so as to cause them to lie substantially at right angles to their original direction and substantially 50 parallel to each other and for holding them in their new position, and means for introducing a slug of celluloid into each of said ends, said last means comprising dilating needles for distending the ends, and cam means for simultaneously advancing said needles into the respective ends.
18. A machine of the class described comprising means for positioning a run of tubular lace material, means for severing said run at an intermediate point, turning and holding devices engageable with the severed ends of the run to turn the lace material at each side of the cutting point at an angle to its original position and to hold it in said position, means for introducing a slug of celluloid into each of said severed ends of the lace material, and means for actuating the cutting, turning and slug introducing instrumentalities in timed relation.
19. A machine of the class described having means for introducing tip-forming material into the end of tubular lace material and lace holding means associated therewith, said last-named means comprising opposed clamping elements for holding the end portion of the lace material in a predetermined position during the introduction of the tip-forming material.
20. A machine of the class described having means for introducing tip-forming material into the end of tubular lace material and lace holding means associated therewith, said last-named means comprising opposed clamping elements, said clamping elements being relatively yieldable to admit the end portion of the lace material between them.
21. A machine of the class described having means for introducing tip-forming material into the end of tubular lace material and lace holding means associated therewith, said last-named means comprising a fixed member and a relatively movable member for positioning the end portion of the lace material, said members having opposed surfaces for gripping the lace material between them, one of said surfaces being yieldable.
22. A machine of the class described having means for introducing tip-forming material into the end of tubular lace material and lace holding means associated therewith, said last-named means comprising opposed clamping elements, one of said elements being rigid and substantially flat and the other consisting of a spring having a substantially flat surface opposed to the flat surface of the fixed element.
23. A machine of the class described having means for introducing tip-forming material into the end of tubular lace material and lace holding means associated therewith, said last-named means comprising a reciprocating holder provided with a recess in one of its sides, resilient means disposed within said recess constituting one element of a clamp for

- positioning one end portion of the lace material, and a fixed member having a substantially flat surface with which the recessed side of said holder engages when the holder is at 5 one end of its path of travel.
24. A machine of the class described having means for introducing tip-forming material into the end of tubular lace material and lace holding means associated therewith, said 10 last-named means comprising a reciprocating holder provided with a spring clamping jaw, a fixed jaw having a substantially flat face, and means for reciprocating the holder in a path parallel to the flat face of the fixed jaw.
- 15 25. A machine of the class described having means for introducing tip-forming material into the end of tubular lace material and lace holding means associated therewith, said last-named means comprising a reciprocating 20 holder, a spring secured to said holder, said spring consisting of flat spring metal bent to provide substantially parallel legs, means attaching one leg to the holder, the other leg being free, the bend of the spring presenting 25 its convex surface in the direction of operative advance of the holder, and a fixed abutment surface opposed to the free leg of the spring.
- 30 26. A machine of the class described having means for applying tip-forming material to the end of lace material and lace holding means associated therewith, said last-named means comprising a fixed abutment having a substantially flat surface for engagement by 35 one side of the end portion of the lace material, and a member movable in a path substantially parallel to said surface, said movable member having a round nosed resilient element opposed to said flat surface and engageable with the opposite side of the end 40 portion of the lace material.
27. A machine of the class described having means for introducing tip-forming material into the end of tubular lace material and lace 45 holding means associated therewith, said last-named means comprising a reciprocating holder provided with a recess in one of its sides, cam means for reciprocating the 50 holder, a spring mounted upon the holder, said spring having a flat leg disposed in the recess, the spring having a smoothly rounded surface at that end thereof which is in advance during the operation stroke of the 55 holder, and a fixed abutment having a surface which is opposed to the flat leg of the spring at the completion of the advancing movement of the holder.
- 60 28. A machine of the class described having means for introducing tip-forming material into the end of tubular lace material and lace holding means associated therewith, said last-named means comprising clamping elements 65 for holding the portions of the lace material in predetermined position, and means for moistening the lace material held between said clamping elements.
29. A machine of the class described having means for applying tip-forming material to the end of lace material and lace holding 70 means associated therewith, said last-named means comprising opposed clamping members for positioning the end portion of the lace material, a fluid supply reservoir, and means for conducting fluid from the reservoir to the clamped portion of the lace material.
- 75 30. A machine of the class described having means for applying tip-forming material to the end of lace material and lace holding 80 means associated therewith, said last-named means comprising opposed clamping members for positioning the end portion of the lace material, a fluid supply reservoir, and a conduit leading from the reservoir through one of said clamping members for delivering fluid to the lace material clamped between 85 said members.
31. A machine of the class described having means for introducing tip-forming material into the end of tubular lace material and lace holding means associated therewith, said last-named means comprising opposed clamping members for holding the end portions of the lace material in a predetermined 90 position between them, one of said members having an aperture in its lace-engaging wall forming an outlet for a chamber within said member, absorbent material filling said chamber and engaging the lace material disposed across the aperture, and means for supplying fluid to said chamber to moisten the absorbent material.
- 95 32. A machine of the class described comprising an abutment member having a chamber therein and an aperture leading from the chamber to an outer face of the member, absorbent material within the chamber and aperture, means for supplying fluid to moisten said absorbent material, and means for resiliently pressing a piece of lace material against the apertured face of the abutment member to permit it to abstract fluid from the absorbent material in the aperture.
- 100 33. A machine of the class described having means for applying tip-forming material to the end of lace material, said means comprising opposed clamping members for positioning the end portion of the lace material, a fluid supply reservoir, the delivery of fluid from said reservoir being barometrically controlled, and a conduit leading from the reservoir to one of the clamping members, said member having absorbent material exposed for contact with the clamped lace material and to which fluid from the conduit is delivered.
- 105 34. A machine of the class described comprising means for positioning a run of tubular lace material, means for severing said run 115
- 110
- 115
- 120
- 125
- 130

at an intermediate point, means for turning at least one of the severed end portions of the lace material into a position substantially at right angles at its original position, means 5 for clamping said end portion in its new position, means for moistening the clamped end with celluloid solvent, and means for inserting a slug of celluloid in the clamped end.

35. A machine of the class described comprising reciprocating delivery means for inserting tip-forming material into the end of tubular lace material, a reciprocating device moving in a path transverse to that of said delivery means for supplying predetermined 10 amounts of tip-forming material to the delivery means, and means for feeding tip-forming material into the path of said reciprocating device.

36. A machine of the class described comprising a reciprocating hollow needle for introducing a slug of tip-forming material into the end of tubular lace material, said machine comprising means for advancing a length of the tip-forming material a predetermined distance, and means for cutting a piece from the end of said strip and for moving 20 said piece transversely into said needle.

37. A machine of the class described having a reciprocating pointed needle for introducing a slug of tip-forming material into the end of tubular lace material, said needle having a longitudinal groove, said machine comprising means for longitudinally advancing 25 a length of the tip-forming material

35 a predetermined distance, and means for cutting a piece from said strip and moving the severed piece transversely into the groove in the needle.

38. A machine of the class described having a reciprocating hollow needle for introducing a slug of tip-forming material into the end of tubular lace material, said machine comprising means for longitudinally advancing a length of the tip-forming material a predetermined distance, a reciprocating cutter, and means for advancing said cutter to cut a piece from said strip and for moving said piece transversely to the needle.

39. A machine of the class described having an instrument for introducing a slug of tip-forming material into the end of tubular lace material, means for reciprocating said instrument, said instrument having a cavity for the reception of a slug, a reciprocating 50 member moving transversely to the path of said instrument, means for advancing tip-forming material into the path of the reciprocable member, and means for actuating the reciprocating member to deliver the slug of tip-forming material into said cavity.

40. A machine of the class described having an instrument for inserting a slug of tip-forming material into the end of tubular lace material, means for advancing said instrument to a delivery position and for retracting

it therefrom, feed means tending constantly to advance a length of tip-forming material, means for positively stopping the advance of the material, and means for cutting a slug 70 from said tip-forming material and for delivering the slug to the inserting instrument while the latter is retracted.

41. A machine of the class described comprising means for supporting a rotary reel containing celluloid ribbon, feed rolls tending 75 constantly to advance said ribbon, means for measuring and cutting off a predetermined length from the advancing end of said ribbon, and means including a reciprocating hollow needle for inserting the severed portion of ribbon into the end of tubular lace material.

42. A machine of the class described having an instrument for inserting a slug of tip-forming material into the end of tubular lace material, said machine comprising a pair of shafts constantly driven in opposite directions, a feed roll carried by each shaft, friction drive elements normally transmitting motion from the shaft to the respective rolls 85 but permitting the rolls to slip relatively to this shaft, means for guiding tip-forming material into the bite of the rolls, an abutment for limiting the advance of the tip-forming material delivered by the rolls, and 90 means for severing the end portion of the tip-forming material engaging the abutment and for delivering it to the inserting instrument.

43. A machine of the class described having an instrument for inserting a slug of tip-forming material into the end of tubular lace material, said machine comprising a pair of feed rolls for advancing a length of tip-forming material, constantly operating 100 means including friction clutch elements for driving said rolls, means engageable with the advancing end of the tip-forming material to limit the advance of the latter, and means for cutting a slug from the forward end of 105 said tip-forming material and for delivering said slug to the inserting instrumentality.

44. A machine of the class described having an instrument for inserting a slug of tip-forming material into the end of tubular lace material, said machine comprising means for advancing a ribbon or tip-forming material, a part having a channel for the advancing material, said part having a guide passage intersecting said channel, the passage 115 being of the desired width of the slug and having an imperforate wall constituting an abutment to limit movement of the advancing end of the ribbon, and a cutter reciprocating in said passage transversely of the channel, the cutter snugly fitting the passage 120 whereby to remove a slug of the desired width from the forward end of the ribbon as the cutter advances across the channel.

45. A machine for tipping shoe laces com- 125

prising a part having a guide passage, a reciprocable cutter fitting in and movable along said passage, a second passage at substantially right angles to the first passage, 5 means for advancing a ribbon of tip-forming material along the second passage until its forward end extends across and is stopped by engagement with the wall of the first passage, means for reciprocating the cutter to sever 10 the end of said material and push the severed end along the first passage, and a member reciprocable across the end of the first passage having a cavity for the reception of the severed end, said member being adapted to deliver said severed tip-forming material into the end of a tubular lace.

46. A machine for tipping shoe laces comprising cutting means, a fixed guide rail, a movable shuttle supported by the rail, means 20 for moving the shuttle along the rail thereby to lay a length of lace material in a predetermined path and into engagement with the cutting means, means for associating tip-forming material with the lace material, 25 means for actuating the cutting means to sever the material thereby producing two ends, dies spaced from the cutting means, and means for transferring said ends of the lace material to the dies.

47. A machine of the class described comprising means for gripping a length of lace material at spaced points, means for cutting the material between said points, means for applying tip-forming material to each of the 30 severed ends of the lace material, and means for moving the gripping means, while still holding the material, to another position.

48. A machine of the class described comprising a pair of spaced gripping devices, 40 means for introducing a length of lace material into the gripping devices, means for cutting the material intermediate the gripping devices thereby providing two ends, means for simultaneously applying stiffening material to said ends, a pair of forming dies, and 45 means for simultaneously moving the gripping devices to place the ends of the lace material into the respective dies.

49. A machine of the class described comprising a pair of gripping devices mounted to swing in an arcuate path, means for introducing a length of lace material into the gripping devices to be held by the latter, means for cutting the material intermediate the gripping 55 devices thereby to produce two ends, means for applying tip-forming material to each of said ends, a pair of dies, and means for swinging the gripping devices to place said ends in the respective dies.

50. A machine of the class described comprising a pair of spaced rotary gripping devices each having a plurality of pairs of gripping jaws, means for introducing a length of lace material into one pair of jaws of each 60 gripping device, means for cutting the ma-

terial intermediate said jaws thereby producing two ends, a pair of dies, means for rotating the gripping devices to place said ends within the respective jaws, and means for actuating the dies to compress said ends while simultaneously introducing a length of the lace material into another pair of jaws of each gripping device. 70

51. A machine of the class described comprising a pair of main gripper devices, a pair 75 of auxiliary gripper devices disposed between the main gripper devices, means for laying a length of lace material in a position such as to cause it to engage each of the gripper devices, means for cutting the material at a point intermediate the auxiliary grippers, a pair of dies, and means for moving both main and auxiliary grippers whereby to carry the ends of the material resulting from the cutting operation into the respective dies. 80

52. A machine of the class described comprising a rotary shaft, means for rotating said shaft, an auxiliary gripper secured to said shaft at a point spaced from each end of the latter, a main gripper device journaled to turn freely on said shaft intermediate each auxiliary gripper and the adjacent end of the shaft, and means for rotating the main grippers about the axis of said shaft. 85

53. A machine of the class described comprising a pair of rotary main gripper devices, a pair of oscillatory auxiliary gripper devices disposed intermediate the main gripper devices, means for laying a length of lace material in a position such as to cause it to engage each of the several gripper devices, means for cutting said length of material at a point intermediate the auxiliary grippers thereby producing two ends, a pair of dies, and means for swinging the main and auxiliary grippers to place said ends in the respective dies, and means for closing the dies to grip said ends and for swinging the auxiliary grippers back to their original position. 100

54. A machine of the class described comprising a pair of rotary main gripper devices each having a pair of jaws, one jaw of each pair being pivoted, means for laying a length of lace material between the opened jaws of each of said devices, means for closing said jaws, means for cutting the material intermediate the gripper devices thereby producing two ends, a pair of dies, means for moving the gripper devices to place said ends in the respective dies, and means auxiliary to the main grippers engaging said ends at points nearer their extremities than the main grippers for controlling the ends on their way to the dies. 110

55. A machine of the class described comprising a pair of rotary main gripper devices each having a pair of jaws, one jaw of each pair being pivoted, means for laying a length of lace material between the opened jaws of each of said devices, means for closing said 120

jaws, means for cutting the material intermediate the gripper devices thereby producing two ends, a pair of dies, means for moving the gripper devices to place said ends in the respective dies, and auxiliary grippers each comprising a resilient jaw, said auxiliary grippers engaging said ends at points nearer their extremities than the main grippers and moving simultaneously with the main grippers to control said ends as they move toward the dies.

56. A machine of the class described comprising a pair of rotary main gripper devices each having a pair of jaws, one jaw of each 15 pair being pivoted, means for laying a length of lace material between the opened jaws of each of said devices, means for closing said jaws, means for cutting the material intermediate the gripper devices thereby producing 20 two ends, a pair of dies, means for moving the gripper devices to place said ends in the respective dies, an auxiliary gripper having a spring jaw engaging each of said ends at a point nearer its extremity than the cor-

25 responding main gripper, means for moving the auxiliary grippers simultaneously with the main grippers to control said ends on their way to the dies, means for closing the dies on said ends, means for moving the auxiliary 30 grippers backwardly to release the lace material from their jaws, and means for opening the dies and the jaws of the main grippers.

57. A machine of the class described comprising tip-applying means and tip-shaping 35 means, and means for transferring lace material from the applying to the shaping means comprising an arm provided with a fixed jaw, and a spring jaw secured to the arm and engaging the fixed jaw with resilient pressure, the engaging faces of the jaws diverging at 40 one end to provide a flaring entrance for the lace material, and a tongue mounted upon one jaw and overlapping the other jaw to prevent the lace material from entering too deeply 45 between the jaws.

58. A machine of the class described having tip-applying means, tip-shaping means, and means for transferring lace material from the tip-applying means to the shaping means, 50 said shaping means comprising a normally stationary block carrying spaced dies, guide rods secured to the block, coiled springs encircling said rods and opposing movement of the block from normal position, a reciprocating 55 die block provided with spaced dies co-operable with the dies of the first block, and means for moving the reciprocating block whereby to bring its dies into operative relation to those of the first block.

60. 59. A machine of the class described having tip-applying means, tip-shaping means, and means for transferring lace material from the tip-applying means to the shaping means, said shaping means comprising a normally 65 stationary but reciprocable block carrying a

die, guide members for said block, springs associated with said guide members tending to prevent movement of the block from its normal position, a reciprocating block having a second die member cooperable with the first die member to shape a lace tip, and means for moving the second die member into cooperative relation to the first die member and for continuing said movement whereby to force said block back from its normal position in opposition to said springs.

60. A machine of the class described having means for applying plastic tip-forming material, tip-shaping means, and means for transferring lace material from the tip-applying means to the shaping means, said shaping means comprising a pair of die-supporting devices, a die carried by each device, means for relatively moving said devices to bring their dies into cooperative relation, and means for heating at least one of the dies, the die-supporting devices being provided with extended surfaces exposed to the air to radiate heat.

61. A machine of the class described comprising a reciprocating shuttle having a guide for lace material, a pair of coaxial rotary gripping devices turning about an axis substantially parallel to the path of the shuttle, a cutting device located in a plane intermediate the planes of rotation of the gripping devices, and adjustable means for determining the length of a run of lace material laid by the shuttle in moving in each direction.

62. A machine of the class described having a shaft, a gripper device journaled adjacent to each end of the shaft, means for rotating each gripper device about the axis of the shaft, an anchor shaft at each end of the first-named shaft aligned with the latter, an anchor device carried by each of said anchor shafts, and means connecting each gripper device to the adjacent anchor shaft whereby rotation of the gripper device turns the anchor shaft in time therewith.

63. A machine of the class described comprising a reciprocating shuttle having a guide for lace material, a pair of co-axial rotary gripping devices turning about an axis substantially parallel to the path of the shuttle, a cutting device located in a plane intermediate the planes of rotation of the gripping devices, and a pair of rotary anchor devices coaxial with the gripper devices, said anchor devices being adjustable toward and from the gripper devices for determining the length of the run of lace material laid by the shuttle at each reciprocation.

64. A machine of the class described comprising a fixed guide rail having beveled edges, a shuttle provided with grooved rolls engaging the beveled edges of the rail, an elongate flexible drive element attached to opposite sides of the shuttle, a pulley about which said flexible drive element passes,

means for oscillating said pulley whereby to reciprocate the shuttle along its guide rail, means carried by the shuttle for guiding lace material, and cutting means across which the 5 lace material is laid by movement of the shuttle in either direction along its guide rail.

65. A machine of the class described having tip-inserting and shaping means, a reciprocating shuttle for delivering lace material 10 to the tip-inserting means, and means for reciprocating the shuttle comprising a rotary crank having a crank pin, a reciprocatory rack bar having a transverse slot for the reception of the crank pin, a pinion engaging 15 the rack bar, a shaft actuated by the pinion, a pulley mounted upon the shaft, a cord having its central part wrapped about the pulley, and guide pulleys at the opposite ends of the path of the shuttle, the end portions of the 20 cord passing about the respective guide pulleys and being connected to the shuttle.

66. A machine of the class described comprising a fixed guide rail, a shuttle movable along said rail, a cord secured at its opposite 25 ends to the shuttle, a pulley about which the central portion of said cord passes, means for oscillating the pulley about its axis, traverse guide means for determining the position of the cord upon the face of the pulley, 30 means carried by the shuttle for guiding lace material, and a cutter across which the lace material is laid by the movement of the shuttle along the rail.

67. A machine of the class described comprising a fixed rail, a shuttle comprising a 35 body portion provided with anti-friction means engaging the rail, said shuttle having a depending leg provided near its extremity with a pair of guide rolls, and guide means 40 upon the body of the shuttle for guiding lace material on its way to said guide rolls.

68. A machine of the class described comprising tip-shaping dies, means disposed in a plane other than that of the dies for cutting 45 a length of lace material and applying tip-forming material to the two ends resulting from the cutting operation, means moving in an arcuate path for transferring said cut ends to the dies, and a shuttle moving in a 50 fixed path and having a leg provided with guide means adjacent to its end for laying the length of material across the cutting means.

69. A machine of the class described comprising dies, cutting means disposed in a 55 plane below that of the dies for cutting a length of lace material, means for applying tip-forming material to each of the ends resulting from the cutting operation, means 60 moving in an arcuate path to transfer said ends to the dies, a horizontal guide rail, a shuttle supported by the rail, said shuttle having a depending leg provided with guide 65 means adjacent to its lower end for laying a length of lace material in operative rela-

tion to the cutting means, and means for reciprocating the shuttle along the rail.

70. A machine of the class described comprising a main frame provided with a table, and a tip-inserting unit removably supported by the table, said unit comprising means for cutting off a slug from a length of tip-forming material and for inserting said slug in the end of tubular lace material, and cam means for actuating said cutting and inserting devices, a shaft carried by the main frame, tip-forming dies and lace positioning means carried by the main frame, means carried by said shaft for actuating the dies and positioning means, and connections between said shaft and the cam means, said connections comprising normally engaging clutch elements, and means for disengaging said clutch elements to permit removal of the 80 said unit with its cam means from the table. 85

71. A machine of the class described comprising a main frame provided with a table, and a tip-inserting unit removably supported by the table, said unit comprising means for cutting off a slug from a length of tip-forming material and for inserting said slug in the end of tubular lace material, and cam means for actuating said cutting and inserting devices, a shaft carried by the main frame, and means for transmitting motion 90 from said shaft to said cam means, said transmitting means comprising normally engaging clutch elements which are engageable in but a single relative angular position of their respective shafts. 100

72. A machine of the class described comprising a main frame provided with a table, and a tip-inserting unit removably supported by the table, said unit comprising means for cutting off a slug from a length of tip-forming material and for inserting said slug in the end of tubular lace material, and cam means for actuating said cutting and inserting devices, a shaft carried by the main frame, tip-forming dies and lace positioning 105 means carried by the main frame, means carried by said shaft for actuating the dies and positioning means, and connections between said shaft and the cam means, said connections comprising normally engaging clutch elements, and means for disengaging said clutch elements to permit removal of the 110 said unit with its cam means from the table. 115

Signed by me at Providence, Rhode Island, this 13 day of August, 1927.

GEORGE H. ARMITAGE.
